Company, Detroit, Mich., a corporation of
Delaware

Application September 25, 1936, Serial No. 102,460

6 Claims. (Cl. 200—98)

The present invention relates to crossing protective systems, and in particular provides an improved system and apparatus for controlling the operation of signal devices associated with a crossing between, for example, a highway and a railway.

It has been customary, heretofore, in connection with rail-highway crossings, to cause the approach of a train to the crossing from either direction to actuate the crossing signal devices when the approaching train reaches a point a substantial distance in advance of the crossing, and maintain the signal in operation until the train reaches and slightly passes the crossing. Conventionally, this is accomplished by dividing the railway adjacent to the crossing into two signaling sections, the junction between which is located at the crossing, and each of which sections extend a substantial distance in a corresponding direction from the crossing. A relay and a source of current are provided at each section. The entrance of the train into either section actuates the relay associated therewith, which action places the crossing signal or signals in operation. The departure of the train from the section restores the track relay to its original condition, extinguishing the signal. In order to prevent the signaling devices from being maintained in operation as long as the train is in the out-going section, electrical and mechanical inter-locking has been employed to cause the operation of the relay associated with the oncoming section to lock out the relay for the out-going section.

In cases where the crossing to be protected is relatively wide, it often has been found desirable to provide three separate signaling sections for each crossing, one of which extends from a point a short distance from one side of the crossing to a point corresponding distance from the other side of the crossing, and the other two of which extend in opposite directions from the respective ends of the central or crossing section. In using the three separate sections, it is desirable that a train approaching a crossing from either direction be effective to actuate the crossing signals upon entering the approach section from the corresponding direction, and to maintain the signals in operation until it has passed completely out of the central or crossing section. It is further desirable that inter-locking be provided so that a train is ineffective to actuate the signals during its passage through the out-going approach section.

It frequently occurs that a highway or other

road crosses the railroad at or near the location of a rail turn-out or siding. In such instances, a train coming on to the main track by way of the siding or turn-out will reach the main track at a point included within the central or highway section. In such instances, it is desirable that the approach of the train on the turn-out be effective to actuate the signals and maintain them in operation until the train passes out of the central or highway section. It is desirable also that inter-locking be provided to prevent the operation of the signals during the time that the train is passing through the approach section on the out-going side.

With the foregoing and other considerations in view, objects of the present invention are to provide a crossing control system embodying a central or crossing section, and one or more approach sections extending from the respectively opposite ends of the central section, and so arranged that the entrance of a train or other vehicle into either approach section is effective to actuate the crossing signal devices and to maintain such devices in operation until the vehicle passes through the central section; to provide such a system so arranged that the signaling devices are extinguished when the vehicle passes out of the central section, and are not operative during the time the vehicle is passing through the "approach" section at the out-going side of the crossing; to provide such a system so arranged that the just stated operation is effected independently of the direction from which the crossing is approached; to provide such a system embodying relay mechanisms individual to the respective approach sections and to the central section, and including means for inter-locking such relay mechanisms; and to provide such an arrangement embodying means for mechanically inter-locking the respective relay mechanisms.

Further objects of the present invention are to provide a crossing protective system of the above stated character, embodying means for inter-locking the relay mechanisms for the respective sections in such a way that a vehicle entering the central section inter-locks and prevents operation of the relay mechanisms for both of the approach sections, which inter-locking remains effective as long as the vehicle is in any of the sections associated with the crossing.

Further objects of the present invention are to provide, for use in a crossing protective control system of the above stated character or the like, an improved inter-locking relay structure embodying three sets of operating coils, contact

controlling armatures individual thereto, and mechanical interlocking mechanism arranged between the respective armatures; and to provide such a structure in which the inter-locking mechanism may be added to existing inter-locking relay structures.

With the above and other objects in view which appear in the following description and in the appended claims, preferred but illustrative 10 embodiments of the present invention are shown in the accompanying drawings, throughout the several views of which corresponding reference characters are used to designate corresponding parts, and in which:

15 Fig. 1 is a view in front elevation of a preferred construction of one embodiment of a three element inter-locking relay of the present invention;

20 Fig. 2 is a view in front elevation taken along the lines 2—2 of Fig. 1;

Fig. 3 is a fragmentary view in perspective, illustrating further details of the inter-locking mechanism of the structures of Figs. 1 and 2;

25 Fig. 4 is a fragmentary view in perspective of a modified adaptation of an embodiment of the invention;

30 Figs. 5 through 11, inclusive, are comparative views illustrating various operating positions of the inter-locking mechanism of the relay structure shown in Fig. 4;

Fig. 12 is a schematic diagram of a control system embodying the invention.

Referring first to Figs. 1, 2 and 3, the relay there shown is of the three element inter-locking type, based upon the arrangement shown in Lockhart Patent No. 1,799,629, granted April 7, 1931, and is illustrated as embodying three operating coils, A, B, C, carried upon an insulating support 23. Although only three operating coils 35 are shown, for convenience, it will be appreciated that each coil may be replaced by a set of two or three coils operating upon the same armature. The cores 22, 24 and 26 of coils A, B and C extend through the supporting member 20, and 40 terminate in enlarged pole pieces 28, 30 and 32, respectively.

The coil A controls an armature 34, pivotally connected thereto by a pin 36, carried by the pole piece 28. Armature 34 is provided with an arm 45 38, removably secured thereto, which carries a contact carrying finger 40. In the positions of the parts illustrated in Fig. 2, the contact 42 carried at the end of finger 40 is in engagement with a stationary front contact member 44, which is supported from the member 20, and is electrically connected to a conventional terminal 46. Except as influenced by the hereinafter described inter-locking mechanism, de-energization of coil A permits finger 40 to rotate by gravity in a counter-clockwise direction as viewed in Fig. 2, to a position in which the contact point 42 engages stationary back contact point 48, in turn carried by the supporting member 20 and electrically connected to a usual terminal 50.

It will be appreciated that coil A may be provided with additional moving and stationary contact points, dependent upon the signal requirements of the system with which the relay is associated, the illustrated contacts being sufficient to show the adaptation of the relay to the control of both front and back contacts. Coils B and C are provided with moving and stationary contacts which correspond in all respects to those associated with coil A, the upper stationary 55 front contacts for coils B and C being designated

52 and 54, respectively; the lower stationary back contacts for these coils being designated respectively 56 and 58; and the moving contact points being designated as 60 and 62, respectively.

To effect the inter-locking action, the armature 34, 36 and 38 are provided with extensions 64, 66 and 68, respectively, which are in turn provided with resilient fingers 70, 72 and 74. Fingers 70, 72 and 74 are biased to the illustrated 10 positions, parallel with the armature extensions, by oppositely disposed members associated therewith and connected to the associated armature extension. The members associated with finger 70 are designated 76 and 78, member 76 bearing 15 upon the top of finger 70 and member 78 bearing upwardly upon the bottom of finger 70. The members for the other fingers are similarly constructed and arranged.

The armature extensions 64 and 68, associated with the electro-magnets A and C, respectively, are provided with relatively resilient fingers 80 and 82, respectively, the outer ends of which are downwardly bent to provide shoulders 84 and 86. Arms 88 and 90, of somewhat heavier 20 metal, are disposed immediately below the resilient fingers 80 and 82, to limit the downward movement thereof relative to the associated armature extensions, and to also support the associated armatures, as hereinafter described.

25 The mechanism for interconnecting the various interlocking elements comprises the two members 92 and 94, which are pivotally supported on trunnions 96, 98 and 100, which are carried in U-shaped brackets 102, 104, 106. The brackets 30 are directly supported by the relay supporting member 20. Member 92 is provided at one end with an upstanding finger 110, which normally lies below and in slightly spaced relation to the shoulder 86 formed at the end of the resilient finger 80; an operating finger 112, which normally lies below and in spaced relation to the resilient finger 72; and a second operating finger 114, which normally lies below and in spaced relation to the resilient finger 74. One or more counter-weights, such as 116, are preferably provided to bias member 92 to the illustrated position. Stops such as 117 limit angular movements of member 92. The other connecting member, 94, is provided with an upstanding finger 120, corresponding to finger 110, and disposed in corresponding relation to the shoulder 86 of the resilient finger 82; and is also provided with operating fingers 122 and 124, corresponding to the operating fingers 112 and 114, and correspondingly related to fingers 70 and 72. It is noted that finger 72 is broad enough to span both of the operating members 112 and 122. Member 94 is also provided with counterweights such as 126 to bias it to the illustrated position, and with stops, such as 117 for member 92, to limit angular movements.

35 In operation, the coils A, B and C are normally energized and so maintain the armatures 34, 36 and 38 in the positions illustrated in the various figures, in which positions the moving contacts 42, 52 and 62 engage the upper stationary front contacts 44, 54 and 56, respectively. In the normal positions of the parts also, the two fingers 38 and 82 are disposed slightly above the inter-locking fingers 110 and 120, respectively, and the inter-locking fingers 70, 72 and 74 lie above and in spaced relation to the operating fingers 112, 114, 122 and 124.

40 Assuming, for example, that the electro-mag- 75

net A is de-energized, the armature 34 thereof falls by gravity in a counter-clockwise direction as viewed in Figs. 2 and 3, during the course of which movement the moving contact 42 tends to be moved out of engagement with the upper stationary contact 44. In certain instances, it is desirable to so arrange the contact structure that even a slight initial movement of the armature is sufficient to move the moving contact away from the stationary contact 44. In certain other instances, such for example, as in the hereinafter described control system, it is preferred to utilize contacts of the so-called "flagman" type, that is, contacts so arranged that a substantial initial amount of movement of the armature is required to move the moving contact 42 away from the stationary contact 44. Specifically, it is preferred to so arrange the construction that the moving contact 42 remains in engagement with the stationary contacts 44 unless the armature moves farther than the hereinafter described mid-position, as provided by the inter-locking mechanism. This may be accomplished, as will be appreciated, by forming the contact finger 40 of resilient material and arranging it so that in the illustrated position of the parts, the finger 40 is stressed somewhat. In the instance being assumed, armature 34 falls to its lowest position, bringing contact 42 into engagement with contact 48.

Continuing the operation resulting from a de-energization of the electro-magnet A, the downward movement of the armature 34 thereof brings the finger 70 into engagement with the operating finger 124 associated with member 94, and rotates the latter member in a clockwise direction as viewed in Fig. 3, to a position in which the upper end of the finger 120 lies behind the shoulder 86, and beneath and in spaced relation to the outer end of the supporting finger 90. During the downward movement of the armature 34 of electro-magnet A, the shoulder 84 of finger 80 bears upon the upper end of the finger 110, which action, however, due to the light construction of finger 80, does not interrupt the downward armature movement. With the parts in the just stated position, it is believed to be evident that the armature 38 is mechanically locked against movement to the lower position, since, upon de-energization of the electro-magnet C, the finger 90 which, as previously stated, is heavy enough to maintain the armature 38 in the upper position, moves downwardly upon and is supported directly by the upstanding finger 120. The only effect of a de-energization of the electro-magnet C under the just stated conditions, is to permit its armature to fall to the mid-position, in which the shoulder 86 lies in front of the hook shaped end of the finger 120.

Assuming now that the electro-magnet A is re-energized, the armature 34 thereof is drawn upwardly, moving the finger 70 upwardly out of engagement with the operating finger 124. In response to this action, due to the counter-weight 126, the connecting member 94 tends to rotate in a counter-clockwise direction as viewed in Figs. 2 and 3, to relieve the finger 120 from the fingers 86 and 82. This action is, however, prevented by the shoulder 86, unless the electro-magnet C is energized. In the latter event, shoulder 86 is raised above the level of the end of finger 120, permitting the latter to move outwardly therefrom into the initial illustrated position.

It will be seen, therefore, that a de-energization of electro-magnet A during the energized

condition of electro-magnet C, applies a mechanical lock to the armature of electro-magnet C, which mechanical lock, while permitting movement of the armature 38 to an intermediate position, prevents movement thereof to the lower position. It will also be seen that the mechanical lock thus applied is rendered ineffective upon the re-energization of the electro-magnet A, only in the event that the electro-magnet C is energized. It is believed to be evident, in view of the similar relation which exists between the armatures 34 and 38, that a de-energization of electro-magnet C during the energized condition of electro-magnet A, imposes a mechanical lock upon the armature 34 which duplicates in all respects the just described mechanical lock for armature 38.

In view of the fact that the armature 36 associated with the electro-magnet B is not provided with the locking member corresponding to fingers 84 and 80 of armature 34 and fingers 82 and 90 of armature 38, the armature 36 is free to move to its lower position independently of the energized or de-energized condition of the electro-magnets A and C. Movement of armature 36 to the de-energized position, however, imposes the just described mechanical lock to both armatures 34 and 38, independently of whether these armatures are in the energized or de-energized position at the time that the de-energization of electro-magnet C occurs. Assuming, for example that the parts are in the normally energized position shown in the figures, a de-energization of electro-magnet B permits armature 36 to fall to its lower position, during the course of which movement finger 72 engages both of the operating fingers 112 and 122, consequently rotating both locking members 92 and 94 in the clockwise direction as viewed in Figs. 2 and 3. These actions lock both the armatures 34 and 38 against movement to the lowest positions thereof, in the manner described above. If, during the de-energized condition of electro-magnet B, either or both of electro-magnets A and C are de-energized, the armatures thereof fall to the intermediate positions, in which positions they are retained by the engagement between the supporting fingers 88 and 90 thereof with the fingers 110 and 120, respectively. In the last mentioned positions also the shoulders 84 and 86, respectively, overlie the hook shaped ends of the fingers 110 and 120 and provide locks which prevent members 92 and 94 from rotating to the unlocked position, even though the electro-magnet B is re-energized. The unlocking of electro-magnets A and C may, therefore, be accomplished only by energizing both such magnets. If the de-energization of electro-magnet B occurs at a time when either electro-magnets A or C is de-energized, the locking action is the same as just described since in this instance the fingers 110 and 120 may be swung under the fingers 80 and 82, respectively, even though fingers 80 and 82 may be bearing thereon.

In the modified arrangement of Fig. 4, the electro-magnets A, B and C are provided with armatures 34, 36 and 38 corresponding in all respects to the previously described armatures and which armatures may also be provided with correspondingly constructed and arranged moving and stationary contacts. The moving and stationary contacts are not shown in the drawings in order to simplify them. The inter-locking structure between the armatures 34 and 38 of Fig. 4 is similar in many respects to that disclosed in Patent No. 1,824,131, granted September 22, 75

1931, to O. S. Field, and comprises generally a pair of bell crank members 130 and 132, provided with hook shaped ends 134, 136, respectively, and pivotally connected as by pins 138 and 140 to a supporting member 142 which may be formed integrally with or suitably secured to the supporting structure for the relay. The bell crank members 130 and 132 are provided with counter-weights 144 and 146, which bear upon and are supported by a member 148 which is stationary with respect to the member 142, and also acts to provide a support for the outer ends of the pins 138 and 140. As will be appreciated, the counter-weights 144 and 146 urge the ends 134 and 136 of the bell cranks away from each other to the positions illustrated in the figure. The bell cranks 130 and 132 are provided with shoulders 150 and 152, respectively, which normally lie below and in spaced relation to the outer ends of operating fingers 154 and 156, which are directly connected to the armatures 34 and 38.

The just described elements effect an interlocking between the armatures associated with electro-magnets A and C which is functionally equivalent to that provided in the previously described embodiment, in the manner described in the above identified Field patent. As described in that patent a de-energization of electro-magnet A occurring during the energized condition of electro-magnet C permits the arm 154 to move downwardly into engagement with the shoulder 152 of the bell crank 130, which action rotates the latter in a counter-clockwise direction as viewed in Fig. 4, bringing the tip 134 thereof above and in the path of movement of the tip 136 of the opposing bell crank 132. The downward movement of the armature 34 of electro-magnet A also actuates the movable contact finger 48 thereof in the usual way.

40 A de-energization of electro-magnet C occurring during the de-energized condition of electro-magnet A, permits the operating arm 156 to move into engagement with the shoulder 152 of bell crank 132, tending to rotate the latter in a clockwise direction as viewed in Fig. 4. The rotation thus produced is interrupted at an intermediate point in the downward movement of the armature 38 of electro-magnet C, by the engagement of the lower end of bell crank 132 with the under-side of lower end of bell crank 130. In the limit position thus provided, the hook 136 at the end of bell crank 132 lies behind and below the lower end of bell crank 130.

Assuming now that electro-magnet A is re-energized, the armature 34 thereof lifts the operating arm 154 out of engagement with the shoulder 152 of bell crank 130. The counter-weight 144 associated with bell crank 130 tends to rotate the latter in a clockwise direction to restore it to the position illustrated in Fig. 4. Such rotation is, however, prevented by the just mentioned hook 136. The parts thus remain in position to lock the armature 38 of electro-magnet C, until such time as electro-magnet C is re-energized to lift member 156 away from bell crank 132 and permit it, as well as bell crank 130, to resume the illustrated position.

It is believed to be evident that a reverse action occurs in the event electro-magnet C is first de-energized, in which case bell crank 132 moves to a position to block bell crank 130, and the hook 134 at the end of bell crank 130 becomes effective to prevent a return movement of bell crank 132.

75 In accordance with the present invention, in

order to render electro-magnet B effective to lock out both of electro-magnets A and C, the armature 36 of electro-magnet B is provided with a finger 160, which normally lies above and in slightly spaced relation to one end of a bell crank 162. Bell crank 162 is pivotally connected, as by a pin 164, to a bifurcated member 166 which may be formed integrally with or suitably secured to the relay supporting structure. The outer and upwardly turned end 168 of bell crank 162 is provided with an oppositely shouldered inter-locking tip 170. The tip 170 is disposed, upon de-energization of the armature 36, to be moved upwardly between the bell cranks 130 and 132, to thereby form a stop to limit movements thereof, and lock the same in the intermediate positions.

A typical operating sequence of the complete structure of Fig. 4 is shown in the comparative views, Figs. 5 to 9. In Fig. 5, both of the operating arms 154 and 156 are in their normal upper positions, corresponding to an energized condition of both electro-magnets A and C, and the shouldered tip 170 is in its normal lower position, corresponding to an energized condition of the electro-magnet B. Assuming that the electro-magnet A is de-energized, the arm 154 falls to the lower position shown in Fig. 6, rotating the bell crank 130 in the counter-clockwise direction to the position shown in Fig. 6, in which position, as previously described, it is effective to block movement of bell crank 132, and so limit a downward movement of the armature associated with electro-magnet C to a halfway point.

Assuming now that during the de-energized condition of electro-magnet A, electro-magnet B is de-energized, the parts assume the positions shown in Fig. 7, in which the shouldered tip 170 lies in blocking relation to the end of bell crank 132, and is also effective to prevent a return movement of bell crank 130 to the original unlocked position. Thus, as long as electro-magnet B is de-energized, the energized or de-energized condition of electro-magnet A is immaterial, so far as concerns the locking out of the armature associated with electro-magnet C.

Assuming further that the electro-magnet C is now de-energized, the parts assume the positions shown in Fig. 8, in which the hook 136 formed at the lower end of bell crank 132 is interlocked with a corresponding shoulder of tip 170 and so retains both tip 170 and bell crank 130 in the locking position. Thus, assuming a prior de-energization of either electro-magnet A or electro-magnet B, and a de-energization of electro-magnet C, prior to the re-energization of electro-magnet A or electro-magnet B as the case may be, or both, the armatures of electro-magnets A or B, or both, remain locked until such a time as electro-magnet C is again re-energized. Fig. 80 9 illustrates the relation that a re-energization of electro-magnet A does not release either bell crank 130 or tip 170 from bell crank 132.

The remaining two figures, 10 and 11, illustrate, as will be evident, that an initial de-energization of electro-magnet B projects tip 170 into the space between bell cranks 130 and 132 and locks out the armatures associated with both electro-magnets A and C. Also as shown in Fig. 11, a de-energization of either electro-magnet 70 A or electro-magnet C during the de-energized condition of electro-magnet B, prevents either electro-magnet A or electro-magnet C from being unlocked even though electro-magnet B is re-energized, until such time as both electro-magnet 75

A and electro-magnet C are again re-energized.

It is believed to be evident from the foregoing that the inter-locking between the armatures associated with the respective electro-magnets A, B and C, utilizing either the inter-locking mechanism of Figs. 1, 2 or 3, or that of Fig. 4, may be utilized in a wide variety of signaling situations. Two typical situations are those outlined generally in the forepart of the present specification.

10 In one of these, the electro-magnet B is associated with the central section at an intersection to be protected, and the electro-magnets A and C are associated with approach sections at either side of the intersection. A vehicle in passing the

15 crossing, therefore, sequentially de-energizes the electro-magnets either in the order A, B, C, or in the reverse order, depending upon the direction of travel of the vehicle. The re-energization of the electro-magnets occurs in the same relative order as the de-energization thereof. Where the vehicle is longer than the central section, a period occurs during each passage during which all three electro-magnets are de-energized. Where the vehicle is shorter than the length of the central section, the re-energization of the electro-magnet associated with the approach section on the on-coming side is always re-energized prior to the deenergization of the electro-magnet associated with the approach section on the out-going side.

20 25 30 35 In either instance, the resultant operation is such that the signals or other devices associated with the crossing are actuated when the vehicle enters the approach section on the incoming side; remains in the actuated state until the vehicle passes completely out of the central section, at which time they are restored to their original position; and are prevented from operation by the interlocking mechanism during the passage of the vehicle through the approach section on the out-going side.

40 The second previously mentioned illustrative situation is one in which, in connection with rail-ways, a siding is associated with the main track, which siding enters the main track at a point within the central section. In such cases, trains coming into the main track by way of the siding first de-energize the electro-magnet B associated with the central section and thereafter de-energize the electro-magnets A or C associated with the approach section on the outgoing side. Alternatively, a train entering by way of one of the approach sections and turning off on the siding first de-energizes the electro-magnet for the approach section on the oncoming side and thereafter de-energizes the electro-magnet for the control section. In the one case the signals are actuated to signaling condition as the train enters the central section by way of the siding, and are extinguished at the time the train passes out of such a section. In the other case, the signals are actuated at the time the train enters the approach section on the oncoming side and remain actuated until the train passes completely through the central section.

45 50 55 60 65 Referring now to Fig. 12, the tracks 180 and 182 of an illustrative railway are divided by conventional rail joints a, b, c and d into three sections a—b; b—c; and c—d. Section b—c extends through the intersection between the railway and an illustrative highway or other roadway H; the section a—b extends in one direction from the crossing from the central section, and the remaining section c—d extends in the other direction from the crossing adjacent the central section. The respective sections are provided with

conventional sources of track circuit energy, individual thereto, illustrated as comprising batteries B1, B2 and B3, connected across the two rails adjacent one end of the associated section. It will be appreciated that if desired alternating current sources of track circuit energy may be used. The electro-magnets A, B and C of the previously described inter-locking relays are connected across the rails of the respective sections. As illustrated, electro-magnet A is connected across the rails of section a—b; electro-magnet B is connected across the rails of section b—c; and electro-magnet C is connected across the rails of block c—d.

10 15 20 25 30 35 In order to illustrate the adaptability of the present invention to signaling systems of both the normally open and the normally closed type, circuits are shown utilizing both normally open and normally closed relay contacts. The front or normally open contacts are designated A1, B1 and C1, and these contacts remain closed as long as the associated coils are energized. Contacts A1 and C1 are of the previously identified "flagman" type, that is, are adapted to remain closed except upon movement of the associated armature to the full de-energized position. The remaining contacts are designated as A2, B2 and C2, respectively, and these contacts, as will be appreciated, are open except when the associated coil is de-energized, and the associated armature is in the lowest or unlocked position.

40 45 50 55 60 65 As will be appreciated, the signaling and other elements responsive to the respective relay contacts, may be arranged in various ways, and may be of either the audible or visual type. They may also be of the barrier type shown in the Goodman Patent No. 1,878,234, granted September 18, 1932. The particular nature and arrangement of the signaling devices responsive to the respective relay contacts, form no part of the present invention, and have been illustrated simply as control relays designated as XR and XR1.

In operation, it will be appreciated that as long as no vehicle effective to shunt the tracks occupies any of the above described signaling sections, the respective coils A, B and C are all energized from their associated batteries, and maintain the contacts individual thereto in the positions illustrated in Fig. 12. Under such conditions, the relay coil XR remains continuously energized. Coil XR1, on the other hand, remains de-energized since the circuits provided therefor are open at the parallel connected contacts A2, B2 and C2.

Assuming, for example, that a vehicle enters the section a—b, the shunt circuit between the two rails 180 and 182 provided, for example, through the wheels and axles thereof, so far de-energizes the coil A as to permit the armature associated therewith to fall to the de-energized position, opening the contact A1 and closing the contact A2. This action de-energizes the relay XR and energizes the relay XR1, which correspondingly effect the associated desired signal or control functions.

70 75 80 85 The de-energization of the electro-magnet A also applies the previously described mechanical lock to the armature of the electro-magnet C, this lock being applied either through the structure shown in Figs. 1 through 3, or the structure shown in Figs. 4 through 10, but does not apply an inter-lock to the armature of electro-magnet B.

As the train or other vehicle progresses towards the highway intersection, it passes into the

section *b*—*c*, and correspondingly de-energizes the electro-magnet *B*, the contact *B*₁ of which correspondingly opens and the contact *B*₂ of which correspondingly closes. These actions are without immediate effect in view of the previous deenergization of the electro-magnet *A*. Similarly, the dropping of the armature of electro-magnet *B* due to the de-energization thereof does not modify the mechanical lock previously applied to 10 the armature of electro-magnet *C* by the dropping of the armature of the electromagnet *A*.

As the vehicle continues along the track, and enters section *c*—*d*, the electro-magnet *C* is de-energized, and the armature thereof tends to fall 15 to the lowest position thereof, but is prevented from falling past the so-called half-way point by the mechanical lock initially applied thereto by electro-magnet *A*. The contact *C*₂, therefore, remains open, and the contact *C*₁ remains closed. 20 The de-energization of electro-magnet *C*, however, does render it effective to self-lock itself, as previously described.

As the trailing end of the vehicle passes out of section *a*—*b*, electro-magnet *A* is re-energized, 25 resulting in a re-closure of the contact *A*₁, and a re-opening of the contact *A*₂. These actions are without effect, in view of the now closed condition of contact *B*₂, and the now open position of contact *B*₁. The return of the armature of electro-magnet *A* to unlocking position also is 30 without effect upon the locked condition of the armature associated with electro-magnet *C*, since electro-magnet *B* is now in the de-energized or locking position, and also because of the self-lock applied to electro-magnet *C* by the de-energization thereof.

As the trailing end of the vehicle passes out of section *b*—*c*, electro-magnet *B* is re-energized, and recloses contact *B*₁ and re-opens contact *B*₂. 40 These actions re-energize relay *XR*, and de-energize relay *XR*₁, thus restoring the signaling devices *XR* and *XR*₁ to the initial condition. The re-energization of electro-magnet *B* does not, however, unlock the armature of electro-magnet 45 *C*, the locking relation being maintained in the structure of Figs. 1 through 3 by the shoulder *86* associated with the finger *82* of electro-magnet *C* and in the case of the structure of Figs. 4 through 10, by the hook *136* associated with the bell crank *132*. As long, accordingly, as the vehicle remains within section *c*—*d*, the armature of electro-magnet *C* remains in the locked condition in which it is ineffective to open the contact *C*₁ or close the contact *C*₂.

It will be appreciated, therefore, that in a continuous passage of a vehicle through the three sections, in succession, in the manner just described, the signaling elements *XR* and *XR*₁ are actuated to signaling condition upon the entrance 50 of the vehicle into the initial section; remain in signaling condition during the passage of the vehicle through the initial section and through the central or highway section; and are restored to non-signaling condition upon the departure of the vehicle from the central or highway section.

It is believed to be evident that an operation duplicating the just described operation occurs in the event the vehicle travels in the direction opposite to that just described, in which event the 60 electro-magnet *A* is mechanically locked out.

In certain instances, as stated, it may be expected that the length of the central or highway section *b*—*c* will exceed the length of the vehicle which is traversing the railway, in which event 70 there is an intermediate period during the pas-

sage of the vehicle past the intersection during which period only the electro-magnet *B* is de-energized. In such cases, the operation remains the same as described above, since as previously stated, electro-magnet *B* is effective to lock out both of the electro-magnets *A* and *C*, so that the re-energization of electro-magnet *A* or *C*, as the case may be, as the vehicle leaves the entering section and lies wholly within the central highway section, does not unlock the previously locked 10 electro-magnet.

As also shown in Fig. 12, a rail turnout comprising the two rails *184* and *186* joins the two main rails *180* and *182* at a point lying within the central or highway section *b*—*c*. With this 15 situation, it will be appreciated that vehicles coming on to the main track by way of the turnout rails, do so without passing through either entering section.

The rail turnout may be insulated and bonded 20 in any one of a variety of conventional ways, since the particular details of the bonding and insulating form no part of the present invention. As illustrated, however, insulated rail joints *f* isolate the turnout rails *184* and *186* from the 25 balance of the turnout and are positioned, in accordance with conventional practice, at at least fouling distance from the junction between the main and turnout rails. If desired, of course, the joints *f* may be positioned farther from the 30 crossing than the fouling distance by an amount determined in accordance with the expected speeds of vehicles on the turnout rails. Additional insulating joints *e* are interposed in the turnout rails adjacent the junction between these 35 rails and the main rails in order to prevent short circuiting of the crossing section *b*—*c*. A cross-connector *188* is connected between the turnout rail *184* and the main rail *182*. An equivalent cross-connection between the turnout rail *186* 40 and the main rail *180* is afforded by the usual frog *190*. The switch points *192* and *194* are mechanically connected as by a member *196*, but are insulated from each other by a joint *g*. A jumper *198* is placed around the switch point 45 *192*, in accordance with conventional practice.

It will be appreciated that the just described rail turnout connections do not interfere with the previously described sequence of operation in the event of through travel along the tracks *180* and *182*. 50

If a vehicle approaches on the turnout rails, and passes the rail joints *f*, a shunting circuit for electromagnet *B* is completed, which extends from the main rail *180* through the frog *190* to 55 the turnout rail *186*, thence through the vehicle wheels and axles to the turnout rail *184*, and through the cross-connection *188* to the other main rail *182*. The shunt thus provided de-energizes electro-magnet *B*, causing the contact *B*₁ to open and the contact *B*₂ to close. Contact *B*₁ de-energizes the relay *XR* and the contact *B*₂ energizes relay *XR*₁, which relays function, as previously described, to effect the desired control or signal operations. A vehicle entering the 60 section *b*—*c* by way of the turnout rails *184* and *186* thus actuates the signals in the same way as would a vehicle entering either of the approach sections *a*—*c* or *c*—*d*.

De-energization of the electro-magnet *B*, in 65 addition to actuating the signal equipment, including the relays *XR* and *XR*₁ as just described, also mechanically locks both of the electro-magnets *A* and *B* in the manner previously described in connection with the relays.

As the vehicle traversing the turnout rails passes across the rail joints *e*, and enter upon the main rails *180* and *182*, the shunt circuit for electro-magnet *B* is effected in the usual way directly between the main rails *180* and *182*, through the vehicle wheels and axles. From the time a train passes rail joints *f* until it passes out of the central section *b-c*, a continuous shunt circuit is thus provided for the electro-magnet *B*, and the signals remain in actuated condition throughout such passage.

As the leading end of the vehicle enters the section *a-b* the electro-magnet *A* is de-energized, but, in view of the de-energized condition of electro-magnet *B*, the armature of the electro-magnet *A* is mechanically prevented from falling past the halfway position. The de-energization of electro-magnet *A* is, therefore, without effect upon the signals. As the trailing end of the vehicle passes out of the section *b-c*, the electro-magnet *B* is re-energized, re-closing the contact *B1* and re-opening the contact *B2*, thus restoring the signal relays *XR* and *XR1* to the initial non-signaling positions. The re-energization of electro-magnet *B* does not, however, release the lock from the armature of electro-magnet *A*, since the latter upon being de-energized applies the previously described self-locking feature. Accordingly, the departure of the vehicle from the central section serves merely the purpose of extinguishing the signals.

As the trailing end of the vehicle passes outward beyond the rail joints *a*, electro-magnet *A* is re-energized, and acts to unlock itself and restore all of the inter-locking elements to the original unlocked condition.

In the reverse case, where a train entering the section *a-b* passes on to the turnout rails, the operation is the same as in the case of through travel with the exception that the armature magnet *C* is not de-energized because the vehicle never enters the section *c-d*. The signals are initially actuated at the time the train enters section *a-b*. The signals remain operated until the trailing end of the train passes beyond the rail joints *f*, re-energizing electro-magnet *B*. Electro-magnet *A* having been re-energized by the departure of the train from the section *a-b*, the re-energization of electro-magnet *B* restores the signals to non-signaling position.

Although specific embodiments of the invention have been described, it will be appreciated that various changes in the form, number and arrangement of the mechanical parts of the apparatus, as well as various changes in the electrical relationship between the elements of the improved control system, may be made within the spirit and scope thereof.

What is claimed is:

1. Relay mechanism comprising, in combination, first, second and third operating coils; a movable armature individual to each of said coils; and interlocking mechanism including means for rendering movement of the armature for said first coil effective to control movement of the armature for said third coil and for rendering movement of the armature for said second coil effective to control movement of the

armatures for both said first and third coils; the armature for said second coil being free to move independently of the condition of the armature for said first coil.

2. Relay mechanism comprising, in combination, first, second and third operating coils; a movable armature individual to each of said coils; and mechanical interlocking mechanism engageable with the armatures for said coils for rendering movement of the armature of said first coil effective to control movement of the armature of said third coil and for rendering movement of the armature of said second coil effective to control movement of the armatures for both first and third coils; the armature for said second coil being free to move independently of the condition of the armature for said first coil.

3. Relay mechanism comprising, in combination, first, second and third operating coils, a movable armature individual to each of said operating coils; interlocking mechanism including a member selectively movable from a first position to a second position in blocking relation to the armature for said first coil; and means rendering said armatures for both said second and third coils effective to cause movement of said interlocking member from said first to said second position.

4. Relay mechanism comprising, in combination, first, second and third operating coils; first, second and third movable armatures associated with said coils respectively; a first interlocking member movable into blocking relation to the first armature; a second interlocking member movable into blocking relation to said third armature; means for supporting said interlocking members for movement independently of each other; means rendering said second armature effective to actuate both said interlocking members; and means rendering said first and third armatures respectively effective to actuate said second and first interlocking members.

5. Relay mechanism comprising, in combination, first, second and third operating coils; first, second and third movable armatures associated with said coils respectively; a first interlocking member movable into blocking relation to the first armature; a second interlocking member movable into blocking relation to said third armature; said first and second interlocking members being independently movable and both being disposed for engagement and movement by said second armature, and said first and second interlocking members being disposed for engagement and movement respectively by said third and first armatures.

6. Relay mechanism comprising, in combination, first, second and third operating coils; first, second and third movable armatures associated with said coils respectively; a first interlocking member engageable and movable by said first and second armatures for blocking movement of said third armature; and a second interlocking member engageable and movable by said second and third armatures for blocking movement of said first armature.
